UNITED STATES PATENT OFFICE.

GEORGE W. COMEE AND SAMUEL S. COMEE, OF WASECA, MINNESOTA.

BURIAL-CASKET.

SPECIFICATION forming part of Letters Patent No. 281,024, dated July 10, 1883.

Application filed January 16, 1883. (Model.)

To all whom it may concern:

Be it known that we, GEORGE W. COMEE and SAMUEL S. COMEE, both of Waseca, in the county of Waseca and State of Minnesota, 5 have invented certain new and useful Improvements in Burial Caskets or Cases, of which the following is a full, clear, and exact description.

The object of this invention is to construct 10 a knockdown coffin, burial casket, or case which shall afford increased facilities for shipping or packing away in a small space or compass and be readily put together and secured when required.

15 Reference is to be had to the accompanying drawings, forming part of this specification, in which similar letters of reference indicate corresponding parts in all the figures.

Figure 1 represents a view in perspective 20 of our improved corner as applied to unite one of the sides and one of the ends or two contiguous portions of a coffin or burial-casket. Fig. 2 is a horizontal section of the same, taken as denoted by the irregular line $x x$ in Fig 1; 25 and Fig. 3, an inside face view of the metal corner without its filling-piece detached.

Each corner of the coffin or casket is or may 30 be formed alike, and consists, in part, of an outer concave or bent metal strip, A, extending the full depth of the coffin and inserted at its side edges in recesses, kerfs, or saw-cuts $b b$, made in or down the ends of the sides or contiguous pieces B B, to be united by the corner. Said strip A has any number of 35 oblique cuts or openings $c c$ made in its opposite side marginal portions. These cuts are open or exposed at their outer ends, and those on the same side incline in like directions, but in opposite directions on reverse sides, and 40 form interlocking slots with pins or studs $d d$, arranged to intersect the kerfs $b b$ in the pieces B B when the strip A is inserted up within the kerfs $b b$ for the purpose. This engagement of the strip A with the sides or pieces B 45 B serves to unite said sides or pieces together,

and the same are further secured by screws $e e$, which, on being taken out, admit of the strip A being slid endwise from out of the kerfs $b b$ and from interlocking connection with the pins or stops $d d$, thereby providing in a 50 ready and convenient manner for the knocking down of the coffin when required for shipping it a long distance or for other purposes.

We do not restrict ourselves to any particular number of screws for securing the strip A 55 after it has been inserted to its place, and, if desired, nails may be substituted for the screws.

D is a wooden filling-piece, constructed to conform on its exterior and sides to the interior of the strip A and ends of the sides or pieces 60 B B, and on its inner face to the required configuration of the interior of the coffin. Said filling-piece is slid to its place endwise between the ends of the pieces B B, and serves to stiffen the general construction and to relieve the 65 strip A of strain.

Although it is preferred to construct the metal strip A with oblique slots c in its opposite marginal portions for engagement with the pins or studs d , as described, in some 70 cases these slots or openings c may be omitted, and the bent metal strip A be held in place within the kerfs $b b$, formed in the pieces B B, simply by pins or screws $e e$, of which there may be any number. 75

Having thus described our invention, we claim as new and desire to secure by Letters Patent—

A removable corner for knockdown coffins, 80 burial caskets, or cases, consisting of a metal strip constructed with oblique cuts or openings in its opposite side marginal portions for engagement with pins or studs, arranged to intersect kerfs in the ends of the sides or portions to be united, substantially as specified. 85
